Primary Examiner — Darcie E Gottschalk*Assistant Examiner* — Haley K Schnebele(74) *Attorney, Agent, or Firm* — Womble Bond Dickinson (US) LLP**CLAIM**

The ornamental design for a tray, as shown and described.

DESCRIPTION

FIG. 1 is a perspective view of a tray showing my new design.

FIG. 2 is a left elevation view of the tray of FIG. 1, the right elevation view is a mirror image.

FIG. 3 is a front elevation view of the tray of FIG. 1, the rear elevation view is a mirror image.

FIG. 4 is a top plan view of the tray of FIG. 1.

FIG. 5 is a bottom plan view of the tray of FIG. 1; and, FIG. 6 is a plan view of the tray of FIG. 1 in an unfolded configuration.

In the drawings, the broken lines show portions of a tray that form no part of the claim.
